UNITED STATES PATENT OFFICE.

HARVEY M. GERSMAN, OF CHICAGO, ILLINOIS.

EXPANDED STEEL LOAD-BEARING MEMBER.

Application filed February 9, 1925. Serial No. 7,765.

This invention relates to expanded steel load bearing members.

One object of the invention is to provide an integral trussed load bearing member 5 expanded from a rolled structural shape in which the bonds between the chords and the struts are of greater thickness and therefore of greater strength than the strands which constitute the struts, the truss member 10 thereby without increase of weight or of metal having a greater factor of safety.

A further object is to provide an expanded steel load bearing member in which the strands are stretched to the extent required 15 by the degree of expansion and at the same time are of uniform thickness from end to end.

A still further object is to provide a steel load bearing member which may have a maximum degree of expansion without any weakening of the bonds by which the strands are connected to one another or to the chord portions and without any liability of the strands or bonds being torn or fractured at 25 any point under the weight which the member may be designed to sustain.

In order that those skilled in the art may be fully informed in respect to the manufacture of a load bearing member in which the 30 features of the invention are incorporated I have in the accompanying drawing illustrated not only the load bearing member but also an apparatus and method preferably employed in the production of the same, such 35 apparatus and method forming the subjects of my co-pending applications, Serial Nos. 10,849 and 7,764.

In said drawings:

Figure 1 is a side elevation showing, diagrammatically, apparatus by which the load bearing member may be made.

Figure 2 is a top plan view of the same.

Figure 3 is a cross section showing a preferred form of blank.

Figure 4 is a plan view of a portion of the blank.

Figure 5 is a cross section on the line 5—5 of Figure 1, more particularly showing a phase of the slitting operation.

Figure 6 is a plan view of a portion of the blank conforming to the operation shown in Figure 5.

Figure 7 is a cross section on the line 7—7 of Figure 1, more particularly showing a 55 further phase of the slitting operation.

Figure 8 is a plan view of a portion of the

blank conforming to the operation shown in Figure 7.

Figure 9 is a sectional view of the blank on the line 9—9 of Figure 8. 60

Figure 10 is a cross section on the line 10—10 of Figure 1, more particularly showing the operation of the compensating rolls by which the bar or strand portions produced by the slitting of the blank are caused 65 to be of uniform thickness throughout their extent.

Figure 11 is a plan view of a portion of the blank conforming to the operation shown in Figure 10. 70

Figure 12 is a sectional view of the blank on the line 12—12 of Figure 11. The deformation of the strand portions is shown in this figure on a somewhat exaggerated scale 75 in order to promote clearness of illustration.

Figure 13 is a cross section on the line 13—13 of Figure 1, more particularly showing the operation of the first expansion roll.

Figure 14 is a plan view of a portion of the blank conforming to the operation of Figure 80 13.

Figure 15 is a sectional view of the blank on the line 15—15 of Figure 14.

Figure 16 is a cross section on the line 16—16 of Figure 1, more particularly showing the operation of the second expansion roll. 85

Figure 17 is a plan view of a portion of the blank conforming to the operation of Figure 16. 90

Figure 18 is a sectional view of the blank on the line 18—18 of Figure 17.

Figure 19 is a cross sectional view on the line 19—19 of Figure 1, more particularly showing the operation of the first flattening 95 roll.

Figure 20 is a plan view of a portion of the blank and an adjacent portion of the spreader conforming to the operation of Figure 19. 100

Figure 21 is a sectional view of the line 21—21 of Figure 20, this view also showing the lower portion of the first flattening roll.

Figure 22 is a cross sectional view on the line 22—22 of Figure 1, more particularly showing the operation of the second flattening roll. 105

Figure 23 is a plan view of a portion of the blank and an adjacent portion of the spreader conforming to the operation of Figure 22. 110

Figure 24 is a sectional view on the line

24—24 of Figure 23, this view also showing the lower portion of the second flattening roll.

Figure 25 is a cross section on the line 25—25 of Figure 1, more particularly showing the operation of the third flattening roll.

Figure 26 is a plan view of a portion of the blank and an adjacent portion of the spreader conforming to the operation of Figure 25.

Figure 27 is a sectional view on the line 27—27 of Figure 26, this view also showing the lower portion of the third flattening roll.

Figure 28 is a cross section on the line 28—28 of Figure 1, more particularly showing the operation of the fourth flattening roll.

Figure 29 is a plan view of a portion of the blank and an adjacent portion of the spreader conforming to the operation of Figure 28.

Figure 30 is a sectional view on the line 30—30 of Figure 29, this view also showing the lower portion of the fourth flattening roll.

Figure 31 is a cross section on the line 31—31 of Figure 1, more particularly showing the final flattening and delivery rolls.

Figure 32 is a plan view of a portion of the completed beam.

Figure 33 is a sectional view on the line 33—33 of Figure 32.

Figure 34 is a plan view of the slitted blank which is used for the production of a Warren truss.

Figure 35 is a perspective view of the same at the completion of the stretching of the strand portions.

Figure 36 is a plan view of the completed product in the form of a Warren truss.

Figure 37 is a sectional view on the line 37—37 of Figure 36.

The process by which the expanded beam of the present invention is produced is preferably practiced continuously and may be so practiced in connection with the rolling of the blank. In such case the process starts with the blank as it comes from a rolling mill at a temperature below the flowing temperature but sufficiently high to enable parts of the blank to be stretched, shaped and relocated, the steps of the process being all completed while the blank is within a permissible range.

The expanded beam in its form of greatest advantage and widest range of utility is conceived as an I beam which is preferably fashioned as a lattice truss but may also be fashioned as a Warren truss. In either case the blank delivered by the rolling mill and with which the process of manufacture is started may be of regular I cross section.

The drawings illustrate in detail the production of a lattice truss and for most, if not all, practical purposes it will be suffi-

cient if the struts of the completed beam have a single line of intermediate bonds representing points of intersection, the remaining bonds being the connections between the struts and the chords. The blank for such a beam will have three longitudinal rows of slits arranged in the manner and relation of the slits provided in the blanks from which diamond mesh lath, so called, is produced, that is to say with the slits of each row in symmetrically staggered or break-joint relation to the slits of the adjacent row or rows. While the blank for such a beam may, as stated, be of regular I cross section it is preferably of a modified original cross section which promotes the facility of the slitting operation, such a blank, as B, being shown in Figures 3 and 4 and being provided with parallel flanges 1 and a connecting web 2 which has a wide-angled V cross section that provides angularly related longitudinal web portions 2^a and 2^b.

The operations in the order of their performance are slitting the blank, unifying the thickness of the bar or strand portions and the intermediate bonds, stretching the bar or strand portions, and separating the flanges and pressing the stretched bar or strand portions and the intermediate bonds back into a single common plane. The several elements of the apparatus by which these operations are carried out may, of course, be structurally varied. As diagrammatically shown, the apparatus includes slitting rolls 3 and 4, strand unifying or compensating rolls 5, strand stretching rolls 6 and 7, strand flattening rolls 8, 9, 10, 11 and 12, the rolls 12 also serving as delivery rolls, a spreader 13 which is co-operative with the rolls 8, 9, 10 and 11, and feed rolls 14 which act on the flanges 1 and may be arranged as required or desirable, in some instances being mounted on the shafts of certain of the other rolls and in some instances being mounted on shafts specially provided therefor. The several shafts which carry the rolls above enumerated are indicated at 15 and are mounted in bearings for which housings 16 are provided, the shafts being positively driven from a line shaft (not shown) or otherwise suitably by gearing which is sufficiently indicated by the showing of a gear element 17 for each shaft.

The slitting rolls may be of any well known type. While the slitting may be performed in a single stage it is preferably performed in two successive stages, the first stage by the rolls 3 and the second stage by the rolls 4. In the first stage (Figures 5 and 6) the blank is formed with the central row of slits 100 and in the second stage (Figures 7, 8 and 9) with the outer row of slits 101, these being located close to the web. The modified cross section of the blank is of advantage as will appear from Figures 5

and 7 in that the angle of the portions which are displaced during the slitting to the shearing edges is at no point greater than a right angle and this characteristic provides for greater facility in the slitting operation than is possible where, as in a blank of regular I form, certain portions of the web which would be displaced during the slitting operation would lie at an obtuse angle to the shearing edge. In the first stage of the slitting as effected by the rolls 3 the portion 2^b is moved into a plane normal to and located centrally of the flanges 1 and parts of the portion 2^a (being those parts which provide the intermediate bonds) are similarly displaced while the remaining parts of the portions 2^a are held in their original plane and are thus severed from the adjacent parts of the portion 2^b. In the second stage of the slitting as effected by the rollers 4 the parts of the portions 2^b which during the first stage were held in their original plane are moved into the same plane as the portion 2^a, that is to say a plane normal to and located centrally of the flanges 1, and from this common plane adjacent parts of both of the portions 2^a and 2^b are displaced into a common plane parallel to the plane from which the displacement started, the portions so displaced being thus severed from the web along lines parallel and adjacent to the flanges and leaving in the plane from which the displacement started those portions which provide the bonds between the struts and the chords, i. e., the outer lines of bonds, and if, as preferred, the outer lines of slits be slightly distant from the flanges also leaving chord portions of the web. In Figures 8 and 9 the strand portions are indicated at 102, the portions which provide the intermediate bonds at 103, the portions which provide the bonds of the outer lines at 104 and the chord portions at 105.

The strand portions 102 and the intermediate bond providing portion 103 are, as above explained, displaced incident to the slitting operation in planes parallel to the planes of the outer bond providing portions 104 and the chord portions 105. In consequence of this displacement the length of the parts between successive portions 104, these parts being two strand portions 102 and an intermediate bond providing portion 103 located between them, is greater than the length which these parts had prior to their displacement, that is to say prior to the cutting of the outer slits 101. It follows that as an incident of the slitting operation there is some stretching of the metal of the displaced portions. This stretching occurs in the parts by which the displaced portions are connected to the outer bond providing portions 104, these parts being shown in Figure 9 at 102^a and being terminal parts of the strand portions 102 which extend diagonally from the straight parts of such strand portions to the portions 104. Thus the parts 102^a due to their stretching are of somewhat less thickness than the parts 104 and the straight parts of the strand portions 102. It is desirable, however, that the displaced parts be of equal thickness throughout their extent since, otherwise, the resultant strands would not only be of unequal thickness at different points but the parts stretched during the slitting operation would be further attenuated during the ordered stretching operation, offering as they do less resistance to the stretching forces than the remaining parts, and would therefore be a source of weakness in the finished beam. I therefore provide for compensating the stretch of the parts 102^a by making all parts of the bond providing portions 103 and the strand portions 102 of equal thickness, this end being best served by attenuating the intermediate bond providing portions 103 and the flat parts of the strand portions 102 prior to the ordered stretching operation whereby said flat parts and their connecting portions 103 are increased in over-all length and are reduced to the same thickness as the connecting parts 102^a. This operation is accomplished by a pair of unifying or compensating rolls 5, one acting on the blank from above and the other from below. The rolls 5 are formed with co-operating transverse corrugations which are shaped and arranged to deform the displaced portions of the blank into sinuous outline as shown in Figures 11 and 12, the parts 102^a being included in the sinuous curve at any point of which the metal is of the same thickness as at any other point. It is to be noted that the deformation of the strand portions is shown in Figures 11 and 12 on a somewhat exaggerated scale in order to promote clearness of illustration.

The stretching operation follows the operation of the compensating rolls and is preferably performed in more than one stage, two stages being provided for in the apparatus disclosed. The stretching operation is so performed that the intermediate bond providing portions 103 are offset in paths at right angles to the mean longitudinal plane of the web with the result that the adjacent strand portions at opposite sides of the several slits 100 while remaining in parallel relation are stretched proportionately to the increase in the distance between their ends as measured by their points of connection with the respective bond providing portions 103 and 104. By proceeding in this manner the bending of the strands where they join the bond providing portions is along transverse lines and the stretching forces are applied at right angles to these transverse bending lines with the result that

there is no possibility of tearing. Various mechanical agencies may be employed for offsetting the bond providing portions 103 in order to stretch the strand portions 102. 5 As shown in the drawings the means for this purpose consists of the rolls 6 and 7 which are provided with teeth 6^a and 7^a. These rolls are arranged whereby their teeth enter the angle of the convolution of which 10 the portion 103 provides the apex. As shown in Figure 12 this angle faces downward and the rolls 6 and 7 are accordingly arranged to engage the blank from below. The teeth 6^a act in the first stage of the 15 stretching operation and are therefore of less depth than the teeth 7^a by which the stretching operation is completed. At the completion of the first stage of the stretching operation, as shown in Figure 15, the 20 strand portions 102 have been straightened from the sinuous form which they had when the operation started and have been stretched to a partial extent. At the completion of the second stage of the stretching operation, as shown in Figure 18, the strand 25 portions have been stretched to the degree which may have been determined upon and each stretched part which includes an intermediate bond providing portion and the strand 30 portions thereby connected is displaced into substantial V-form.

The next step is the expansion of the blank into the completed structural section. This involves operations merely for the production of open work and does not involve any sensible stretching of any of the parts. In the expansion of the blank the strand portions are subjected to a two-fold displacement operation, that is to say, they are bent outward relatively to one another so as to extend divergently from the common bond and they are also pushed back into the central longitudinal plane of the web, in short, flattened. These operations are accomplished by moving the flanges of the blank relatively outward and at the same time applying pressure to the offset bond providing portions to move them and the strands back into the central longitudinal plane of the web. By pressing the offset bond providing portions back toward the central longitudinal plane of the web while the flanges are being spread, the rate at which the bond providing portions are pressed back being proportional to the rate at which the flanges are spread or slightly greater, further stretching of the strands is avoided and at the same time all liability of tearing the strands in the directions of the slits is avoided. The flattening of the displaced parts may be effected by various means, the drawings illustrating for this purpose a series of rolls 8, 9, 10, 11 and 12 by which the operation is completed in successive stages. The relative outward move-

ment of the flanges may be effected by various means but is preferably effected by the spreader plate 13 which is employed in co-operation with the rolls 8, 9, 10 and 11, the web passing over the plate 13 which is thus used as a support and the flattening rolls engaging the displaced parts of the web from above. The plate 13 has a close fit between the flanges 1 of the blank and its sides are regularly divergent whereby said plate 70 regularly increases from a width corresponding to that of the web at the end of the strand stretching operation to the width which it is intended that the web shall have in the finished beam, the diverging sides of 75 the plate 13 acting on the flanges 1 during the travel of the blank to cause an increase in the mutual spacing of said flanges corresponding to the regular increase in the width of the spreader. The operation of the first 80 of the flattening rolls is illustrated in Figures 19, 20 and 21 from which it will be observed that the roll 8 has applied pressure to the adjacent portion 103 and forced the same to a lower plane, the flanges 1 have been 85 moved relatively outward to a slight degree by the spreader 13 and the strand portions 102 have adjusted or accommodated themselves to the altered positions of the portion 103 and the flanges 1, the laterally adjacent 90 strand portions now extending from the portion 103 at a slight angle to one another and the longitudinally opposite strand portions now extending from the portion 103 at an increased angle to one another. The 95 operation of the second flattening roll 9 is similarly illustrated in Figures 22, 23 and 24 from which it will be observed that the portion 103 has been forced to a position somewhat below that of Figure 21, the mutual 100 spacing of the flanges 1 has been further increased and that the strand portions have again and in like manner adjusted or accommodated themselves to the further altered positions of the portion 103 and the 105 flanges 1. The operation of the third flattening roll 10 is illustrated in Figures 25, 26 and 27 and that of the fourth flattening roll 11 in Figures 28, 29 and 30. These operations are similar to those of the rolls 8 and 110 9 and involve further increases in the spacing of the flanges 1 and further flattening of the stretched displaced portions.

The fifth and final stage of the expanding operation is performed by a pair of co-operating rolls 12. The spreader 13 projects for some distance in advance of the fourth flattening roll 11 and as the blank is fed forward from this roll a further increase in the spacing of the flanges 1 is effected by 120 the spreader. The rolls 12 act on the blank as it passes beyond the spreader. At this time the flanges 1 have been spaced to the extent determined upon and the flattening 125 of the stretched displaced portions has been 130

nearly completed. The office of the rolls 12 is, therefore, to perform the final step of bringing the displaced portions uniformly into the central longitudinal plane of the 5 web and to give a desirable finish to the completed beam. These rolls are therefore shaped and proportioned to act on all parts of the web and are operative to deliver the completed structural member which is shown 10 in Figures 32 and 33.

The process described results in a finished product which is a beam expanded from a rolled structural shape in which all of the parts displaced by the expansion lie in the 15 central longitudinal plane of the beam, the structure being integral throughout. In the completed product the strands 102^x are of equal thickness throughout their extent, the intermediate bonds 103^x are of equal thickness 20 with the strands and the outer bonds 104^x are of somewhat greater thickness than the strands since they are not subject to any stretching and therefore give a greater factor of safety to the structural member.

25 The above description assumes the production of a lattice truss where the blank has at least three rows of slits but fundamentally the same method can be used for the production of a beam in the form of a 30 Warren truss. In this case the blank is of regular I cross section and, as shown in Figure 34, has two rows of longitudinal slits 106 and 107, those of one row in break-joint relation to those of the other row. 35 Between the ends of the slits 106 are portions 108 which provide bonds between the struts and the chord at one side of the beam and between the ends of the slits 107 are portions 109 which provide bonds between 40 the struts and the cord at the opposite side of the beam. The strand portions 110 are delimited by the overlapping portions of the slits 106 and 107 and lie between each pair of adjacent bond providing portions 108 and 45 109. In the stretching operation each strand portion is bent into substantial V form, the stretching pressure being applied centrally of its length in the same manner in which it is applied to the bond providing portions 50 103 of the blank used for the lattice truss. The blank at the completion of the stretching operation is shown in Figure 35. The expansion of the blank is carried out in the manner previously described, that is to say 55 the spacing of the flanges is regularly increased to the extent determined upon and the bent and stretched strand portions by pressure applied to their apices are simultaneously and at a proportionate rate pressed back into the central longitudinal plane of the beam. The completed structural member 60 is shown in Figures 36 and 37 in which the strands are indicated at 110^x and the bonds at one side at 108^x and those at the other side

at 109^x, the strands being of uniform thickness throughout and the bonds (which are not stretched) being of somewhat greater thickness than the strands and therefore giving the beam a factor of safety. 65

Having fully described my invention, I 70 claim:—

1. An integral load bearing member expanded into truss form from a rolled shape and having stretched open work and unstretched bonds connecting said open work 75 to the sides of said member.

2. An integral load bearing member expanded into truss form from a rolled shape and having stretched open work and unstretched bonds connecting said open work 80 to the sides of said member and being of greater thickness than the parts which provide said open work.

3. An integral load bearing member expanded into truss form from a rolled shape 85 and having stretched strands constituting struts and unstretched bonds at the ends of the strands.

4. An integral load bearing member expanded into truss form from a rolled shape 90 and having stretched strands constituting struts and bonds at the ends of the strands, the bonds being of greater thickness than the strands.

5. An integral load bearing member expanded into truss form from a rolled shape 95 and having stretched strands constituting struts and of uniform thickness from end to end and bonds at the ends of the strands, the bonds being of greater thickness than the 100 strands.

6. An integral load bearing member expanded into trussed form from a rolled shape and having strands constituting struts and bond portions at the ends of the struts, 105 said member being produced by so stretching the strand portions while the shape is heated and prior to expansion as to bend them from the bond portions along transverse lines and by expanding the shape without further stretching the strand portions, thereby giving the member the qualities specified. 110

7. An integral load bearing member expanded into trussed form from a rolled shape and having strands constituting struts, 115 and bond portions at the ends of the struts, said member being produced by so stretching the strand portions while the shape is heated and prior to expansion as to bend them from the bond portions along transverse lines, leaving the bond portions unstretched and of original thickness, and by expanding the shape without further stretching the strand portions, thereby giving the member the qualities specified. 120

8. An integral load bearing member expanded from a rolled shape into the form of a lattice truss and having strands and

outer and intermediate bonds therefor, the strands and the intermediate bonds being stretched and the outer bonds being unstretched.

5. An integral load bearing member expanded from a rolled shape into the form of a lattice truss and having strands and

outer and intermediate bonds therefor, the strands and the intermediate bonds being stretched and the outer bonds being unstretched and of greater thickness than the strands and the intermediate bonds. ¹⁰

In testimony whereof I affix my signature.

HARVEY M. GERSMAN.
